UNITED STATES PATENT OFFICE

168,497

TOY AIRPLANE

Jack A. Calhoun, Long Beach, Calif., assignor to
Skycraft Mfg. Corp., Long Beach, Calif., a corporation of California

Application January 25, 1952, Serial No. 18,243

Term of patent 14 years

(Cl. D34—15)

To all whom it may concern:

Be it known that I, Jack A. Calhoun, a citizen of the United States of America, residing at Long Beach, in the county of Los Angeles, and State of California, have invented a new, original, and ornamental Design for Toy Airplane, of which the following is a specification, reference being had to the accompanying drawing, forming part thereof.

Fig. 1 is a bottom perspective view of a toy airplane, showing my new design;

Fig. 2 is a side elevational view thereof;

Fig. 3 is a top plan view thereof; and

Fig. 4 is a front elevation view thereof.

I claim:

The ornamental design for a toy airplane, as shown.

JACK A. CALHOUN.
